KEY AND COIN COMBINATION LOCK

Robert K. Hensley, Jr., Silver Spring, Md.

Application August 16, 1955, Serial No. 528,665

4 Claims. (Cl. 194—92)

This invention relates to a coin or token controlled device for actuating a closure member such as are used on lockers and the like whereby, upon payment of an indicated amount, access to the interior of the locker through actuation of the closure member can be obtained.

The primary object of the present invention resides in the provision of a coin controlled device in which the number of coins necessary to be inserted to open a locker can be easily controlled by the utilization of movable slug members which are held in a position so as to be retained against unauthorized removal.

A further object of the present invention resides in the provision of a coin controlled device which employs a key of any suitable shape which must be inserted before the device can be actuated.

An additional feature of the invention lies in the novel arrangement of a slide and a channel-shaped guide having flanges overlying recesses for retaining slugs in position against unauthorized removal thereof.

Still further objects and features of this invention reside in the provision of a key and coin controlled actuation device for a locker or other apparatus that is simple in construction, highly efficient in operation, and which is adapted to be utilized in connection with a dry cleaning and laundry establishment for delivery of clothing and the like which have been cleaned without requiring a human attendant at the locality.

These, together with the various ancillary objects and features of the invention which will become apparent as the following description proceeds, are attained by this invention, a preferred embodiment of which has been illustrated in the accompanying drawings, by way of example only, wherein:

Figure 1 is a plan view of the device comprising the present invention;

Figure 2 is a partial vertical sectional view as taken along the plane of line 2—2 of Figure 1 and illustrating the device in a non-actuated position;

Figure 3 is an enlarged vertical sectional detail view as taken along the plane of line 3—3 of Figure 1 illustrating the construction of the slide and guide;

Figure 4 is an enlarged vertical sectional detail view as taken along the plane of line 4—4 of Figure 1 illustrating the construction of the slide and guide with a slug positioned in place;

Figure 5 is a partial plan view showing the device with the slide in a closed position, and with parts of the device being broken away to show other parts in section for greater detail;

Figure 6 is a vertical sectional detail view as taken along the plane of line 6—6 in Figure 1; and

Figure 7 is a side elevational view of a locker employing the present invention.

With continuing reference to the accompanying drawings wherein like reference numerals designate similar parts throughout the various views, the reference numeral 10 is used to generally designate a locker which is adapted

2

to employ the actuation device 12 comprising the present invention. The locker 10 may be formed of any suitable material and may be arranged with others of similar construction in vertically stacked piers and in suitable rows thereof as may be desired. The locker 10 is provided with an opening closed by a front door 14 having a handle 16. The door is hinged at its lower edge as at 18 and permits entry into the central recess 20 thereof in which various articles of clothing, merchandise, and the like may be stored. A partition 22 is provided in the locker 10 and separates the actuation mechanism 12 from the main recess 20.

Secured to the front wall 24 of the locker 10 is a detent support 26 having a detent 28 vertically slidably mounted therein and restrained in its movement by means of a fastener 30 which extends through a threaded bore 32 in the detent holder 26 and engages in a slot 34 in the detent 28. The detent 28 has a portion 36 of reduced cross-sectional area forming a stud and also forming a shoulder 38 against which a coil spring 40 bears, the coil spring 40 also bearing against the surface 42 of the partition 22. The stud 36 extends through an aperture 44 in the partition 22 and also through an aperture 46 in a latch member 48 carried by the door 14. Hence, when the detent 28 is held in a depressed position with the stud 36 extending through the latch member 48, it is not possible to open the door 14.

In order to hold the detent 28 in a depressed position, there is provided a control lever 50 which is pivotally mounted as at 52 on a bracket 54 attached to the side wall 56 of the locker 10.

The lever 50 has a cam 57 on the end thereof engageable by an element 200 on a slide 58 slidably mounted in a guide 60, the guide 60 being secured in the front wall 24 of the locker and extending through a suitable opening formed therein.

The guide 60 is of substantially channel shape, see Figures 3 and 4, and includes a bottom 62 having sides 64 and 66 rising therefrom. Extending inwardly towards each other from the upper portions of the sides 64 and 66 are flanges 68 and 70 which form in conjunction with the slide 58 a comparatively close fit.

The slide 58 is provided with a plurality of apertures as at 72, 74, 76 and 78 therethrough. Also, there is formed in the slide 60 suitable recesses as at 80, 82, 84, 86, 88, 90 and 92, 94 which communicate with the apertures formed in the slide. The apertures 72, 74, 76 and 78 are designed to receive coins or tokens therein and it is noted that slugs, as at 96, can be positioned in the apertures and associated recesses when the slide is in its actuated and inner position in a manner so that because of the overlying position of the flanges 68 and 70, it is not possible to remove the slugs from the slide, thus preventing the insertion of coins in those particular apertures with which the slugs are associated.

A further aperture 100 having associated recesses 102 and 104 is provided in the slide 58 for reception of a key casing 106 having a suitable opening 108 therein for receiving a key 110 of any desired configuration. Because of the removability of the casing 106, the shape of the key for the locker can be changed as may be desired.

An operating handle 112 may be provided for the slide 58.

Mounted on a shaft 114 carried by table studs 116 is a keeper 118 forming stop means for preventing actuation of the slide 58 unless either coins, tokens or slugs are in position, as well as the key 110. The stop means 118 includes a projecting portion 112 that is designed to slide over the key, coins and slugs when they are in position but to abut against the inner peripheral surfaces defined by the respective apertures such as the surface 120, see Figure 2, when the coins or slugs are not in position.

Suitable cams, as at 122, 124, 126, and 128, are positioned on the slide 58 between the respective apertures.

A coil spring 130 is terminally secured to the stop means 118 and to a bracket 132 mounted on the front wall 24 of the device.

In use, the apertures in the slide 58 are designed to receive coins of different sizes or any other suitable number of sizes that may be desired. In the embodiment shown, the apertures 72, 74 and 76 are designed to receive two half dollars each, while the aperture 78 is designed to receive two quarters. Hence, a total of \$3.50 may be deposited in the slide 58 when all of the apertures are empty. However, if it is determined, for example, that it will be necessary to deposit \$2.00 to receive the contents of the locker, a slug, such as the slug 96, may be positioned in the aperture 76 with the wing portions 142 and 144 of the slug seated in the recesses and being retained in position against being withdrawn. Likewise, a suitable slug can be provided for the aperture 78. Then, the patron, after inserting the key 110 in the aperture in the casing provided therefor, and after inserting two half dollars in each of the apertures 72 and 74, may actuate the slide 58 and push it in. The stop means 118 will be held out of position and out of locking engagement with the surfaces, such as the surface 120, by either the slugs or the coins, and thus it is possible to deposit the coins as shown in Figure 5 since the bottom 62 of the guide 60 terminates in such position that the coins and key can drop through. When the slide 58 is pushed inwardly, the operating lever 50 is moved out of overlying position relative to the detent 28, allowing the door 14 to be opened and the contents of the locker to be removed. It is noted that the locker is especially adapted for use in receiving dry cleaning, laundry, and the like in a self service dry cleaning and laundry establishment.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A coin controlled device for actuating closure means comprising a channel-shaped guide, said guide including a bottom plate having upwardly extending sides, flanges extending inwardly towards each other from the upper part of said sides, a slide movably positioned in said guide having at least one aperture therethrough, said slide having recesses therein communicating with said aperture, said flanges overlying said recesses, a casing received in said aperture and said recesses, said flanges overlying said casing, an opening in said casing, and a key receivable in said opening.

2. A coin controlled device for actuating closure means comprising a channel-shaped guide, said guide including

a bottom plate having upwardly extending sides, flanges extending inwardly towards each other from the upper part of said sides, a slide movably positioned in said guide, said slide having a plurality of apertures therethrough, said slide having recesses therein communicating with said apertures, said flanges overlying said recesses, a casing received in one of said apertures and the recesses communicating therewith, said flanges overlying said casing, an opening in said casing, and a key receivable in said opening.

3. A coin controlled device for actuating closure means comprising a channel-shaped guide, said guide including a bottom plate having upwardly extending sides, flanges extending inwardly towards each other from the upper part of said sides, a slide movably positioned in said guide, said slide having a plurality of apertures therethrough, said slide having recesses therein communicating with said apertures, said flanges overlying said recesses, a casing received in one of said apertures and the recesses communicating therewith, said flanges overlying said casing, an opening in said casing, and a key receivable in said opening, a pivotally mounted control lever, a closure detent, said control lever being engageable with said closure detent, said slide being engageable with said control lever.

4. A coin controlled device for actuating closure means comprising a channel-shaped guide, said guide including a bottom plate having upwardly extending sides, flanges extending inwardly towards each other from the upper part of said sides, a slide movably positioned in said guide, said slide having a plurality of apertures therethrough, said slide having recesses therein communicating with said apertures, said flanges overlying said recesses, a casing received in one of said apertures and the recesses communicating therewith, said flanges overlying said casing, an opening in said casing, and a key receivable in said opening, a pivotally mounted control lever, a closure detent, said control lever being engageable with said closure detent, said slide being engageable with said control lever, and stop means engageable with said slide for limiting movement of said slide in said guide unless said aperture has been filled.
